COLLAPSIBLE MOTION PICTURE SCREEN ASSEMBLY

Filed Jan. 25, 1945

FIG. 4.

FIG. 2.

UNITED STATES PATENT OFFICE

2,403,661

COLLAPSIBLE MOTION-PICTURE-SCREEN
ASSEMBLY

Albert B. Hurley, Huntington, N. Y.

Application January 25, 1945, Serial No. 574,567

6 Claims. (Cl. 160—351)

1

This invention relates to improvements in supports for flexible sheets or screens and has for its principal object to provide a collapsible motion-picture-screen assembly which complies with portability requirements of compactness, lightness, rigidity, ease of assembly, and adjustability with respect to the line-of-sight of the audience.

Another and important object of the invention is to provide an improved assembly of the general character described and one constituted of a very small number of subassemblies wherein the parts are permanently joined one to another to prevent the loss of any one of said parts.

Another and specific object of the present invention is to provide a novel, collapsible tensioned-wire frame for a fabric or other flexible screen, and one wherein the wire is not subject to snarling when the frame is in its collapsed condition.

Other objects and advantages will be apparent and the invention itself will be best understood upon reference to the following specification and to the accompanying drawing wherein:

Fig. 1 is a front elevational view of a collapsible motion-picture-screen assembly embodying the invention and completely assembled.

Fig. 2 is an elevational view showing the oppositely located supports or legs for the frame of Fig. 1, in their folded or collapsed condition.

Fig. 3 is a view in perspective of the screen-frame of Fig. 1 in its collapsed condition and

Fig. 4 is a fragmentary view in perspective showing the connections between the frame of Fig. 1 and its supporting legs.

In the embodiment of the invention which has been selected for illustration the several parts of the apparatus form three discrete sub-assemblies, including a collapsible frame or truss (see Fig. 3) and two pairs of legs (see Fig. 2). The frame in the instant case comprises a central, preferably hollow, metal rod 1 and four preferably shorter arms, 2 to 5 inclusive, of similar hollow construction. The arms 2 and 4 are pivotedly secured to an apertured plate 6 at one end of the central rod 1 and the other pair 3 and 5 are pivotedly secured to a similar plate 7 on the other end of the rod 1. As more clearly shown in Fig. 3, the pivot points 2a and 4a for the arms 2 and 4 on the plate 6 are off-set from the central rod 1, whereas the arms 3 and 5 are connected to the plate 7 at points 3a and 5a which are adjacent to the central rod 1. Thus, when the frame is collapsed, the arms 3 and 5 fall between the arms 2 and 4 to form a "bundle" of minimum size.

2

Referring still to Fig. 3, it will be observed that each of the apertured end-plates 6 and 7 has two keys or pins 8 secured thereto, each on its own chain 9. These pins 8 when seated in appropriate apertures 10 in the end plates 6 and 7 serve to maintain the arms 2 to 5 in the position in which they are shown in Fig. 1, i. e. with each pair of arms arranged in the form of a V whose apex lies adjacent to one of the ends of the central rod 1. When thus extended the ends of the arms 2 to 5 inclusive define the corners of a rectangle of an area greater than that of the rectangular screen which it is designed to support.

The perimeter or sides of the rectangle whose corners are defined by the ends of the hollow metal rods 2, 3, 4 and 5, are formed by a wire or cable 11 which extends between the said corners. This cable 11 is broken in one or more places to allow the arms 1 to 5 inclusive to be folded and is tightened at the break by one or more turnbuckles 12. In practice it has been found that the cable is less likely to snarl if it is made up of four discrete sections with the ends of each section permanently secured to the arms which it connects. In this case the top and bottom sections 11a and 11b of the cable are made just long enough to equalize the stress applied to the arms 2, 3, 4 and 5 by the turnbuckles 12 in the other two sections of the cable.

Four springs 13 fastened respectively to the outer ends of the arms 2, 3, 4 and 5 maintain the screen 14 under tension when connected to grommets 15, on the edge or selvage 16 of the screen. Several snap fasteners 17 on the peripheral cable 11 engage other grommets 15a on the selvage 16 and further tighten and secure the screen 14 within its frame.

As previously indicated and as shown in Fig. 2 the two pairs of legs 21, 22 and 23, 24 which support the frame for the screen 14 above the stage or ground comprise separate sub-assemblies. Each of these sub-assemblies includes an apertured plate 25, to which the legs are pivotedly attached, and a short hollow arm or socket 26 which is rigidly affixed to the said plate and protrudes beyond the pivoted ends of the legs. The internal size of each socket 26 is such that it is adapted to receive the end of one of the lower arms 4 or 5 of the frame as shown in Fig. 4. The distance the frame of the screen 14 is supported above the ground is determined by the angular setting of the legs, that is to say, the larger the angle the lower the frame. The apertured plates 25 are each provided with two chained keys 27—28 which when entered into selected ones of the

radially arranged apertures serve to fix the legs in a desired angular position. As shown in the drawing the legs may themselves be provided with key holes but this is not essential provided that the keys 27 and 28 are long enough to extend through the apertured plates 25 and abut the outer surface of the legs.

It will now be apparent that the present invention provides a novel and compact collapsible screen, and one further characterized by the simplicity and economy of its parts and by its ease of assembly.

What is claimed is:

1. A collapsible support for a rectangular screen, said support comprising a plurality of rod-like members, means connecting said rod-like members in the form of a truss wherein the rod-ends define the corners of a rectangle of an area larger than that of said screen, tensionable means connected to said rods adjacent to their said ends and adapted to form the sides of said rectangle, and means disposed in spaced relation along the said sides of said rectangle for securing said screen thereto.

2. A collapsible support for a rectangular screen, said support comprising a plurality of rod-like members, means connecting said rod-like members in the form of a truss wherein the rod-ends define the corners of a rectangle of an area larger than that of said screen, wire-like means connected to said rods adjacent to their said ends and adapted to form the sides of said rectangle, and means disposed in spaced relation along said wire-like means for securing said screen thereto.

3. The invention as set forth in claim 2 and wherein means are provided for applying stress

to said rod-like members through said wire-like screen support.

4. The invention as set forth in claim 2 and wherein said screen-securing means include a plurality of springs disposed respectively at the corners of said rectangle.

5. A collapsible support for a flexible screen, said support comprising a central rod-like member of a length less than that of said screen, a hinge disposed at each end of said member, a pair of rods of duplicate construction extending radially outward from each hinge to define the corners of a rectangle of an area greater than that of said screen, a plurality of wire-like members secured to said rods adjacent to the free ends thereof and adapted to form the perimeter of said rectangle, a plurality of turnbuckles attached to adjacent ends of said wires, for tensioning said wires, and spring means secured adjacent to the said free-ends of said rods for supporting said screen upon said tensioned screen-support.

10 15 20 25 30 35

6. A collapsible support for a rectangular screen, said support comprising three sub-assemblies including a frame and two pairs of supporting legs, said frame comprising a plurality of hinged rods, the free ends of said rods being swingable to define the corners of a rectangle of an area larger than that of said screen and to which rod-ends said screen is adapted to be connected, the legs of each pair being adjustably connected one to the other, and means for removably connecting said pairs of legs respectively to the rod-ends which form two adjacent corners of said rectangle.

ALBERT B. HURLEY.
